UNITED STATES PATENT OFFICE.

EINAR AAGE WINHOLT, OF SPRINGFIELD, ILLINOIS.

OILING DEVICE.

1,307,889.

Specification of Letters Patent. Patented June 24, 1919.

Application filed January 14, 1919. Serial No. 271,134.

To all whom it may concern:

Be it known that I, EINAR AAGE WINHOLT, a citizen of the United States, and a resident of Springfield, in the county of Sangamon and State of Illinois, have invented a new and Improved Oiling Device, of which the following is a full, clear, and exact description.

My invention relates to mechanism for distributing liquids such for instance as oil devices suitable for general use, my more particular purpose being to provide a liquid discharging receptacle of suitable form adapted to be mounted in any one of many different relations and supported in different ways for supplying liquid to machinery of different kinds. The accumulation of liquid within the receptacle, and the periodic discharge of liquid from the receptacle being to all intents and purposes automatic and proportionate as near as practicable to the actual need for discharge of the liquid. Reference is made to the accompanying drawing forming part of this specification, and in which like reference characters indicate like parts in all the views.

The specific device here illustrated is an oil receptacle, arranged for periodically discharging oil upon a movable member carried by the crosshead of a reciprocating engine. This application of my device, however, is merely typical of a general class of application.

Figure 1 is a substantially central section through the liquid dispensing receptacle and parts immediately associated therewith;

Fig. 2 is a horizontal section through the receptacle casing, other parts being removed;

Fig. 3 is a section on the line 3—3 of Fig. 1, looking in the direction of the arrow;

Fig. 4 is a view partly in elevation and partly in section showing my device as used with a mounting differing slightly from that in Fig. 1; and

Fig. 5 is a fragmentary elevation of the structure shown in Fig. 4.

A casing A has the proximate form of a cylinder, and mounted within it is a valve B. Located within the casing above the valve B is a spiral spring C which rests upon the valve and presses upwardly against a fixture D to which the casing A is secured by a threaded connection D D. The fixture D is mounted upon a support E

which may be a metallic arm or shelf or any other stationary member suitable for the purpose. The valve B is at its lower end provided with a frusto-conical surface F which is ground to fit accurately upon a mating seat at the lower end of the casing A. The valve B carries a tripping rod G which extends downwardly through a substantially star-shaped opening H in the casing A. The tripping rod G is rigid relatively to the valve B and is a part thereof. Whenever the tripping rod G is raised up from any cause the valve B is lifted from its seat. The valve B is provided with passages K extending parallel with its axis, in order to facilitate the downward travel of liquid and to insure the presence of a little volume of liquid within the bottom of the cylinder A in suitable position to be readily discharged whenever the valve B is lifted. The passages K are above the seat of the valve and communicate with each other. The passages are merely spaces between three integral portions or ribs K' with which the valve is provided. The fixture D is provided with a passage J which is preferably in the form of a tube and leads upwardly to any suitable source of supply for the liquid lubricant.

In the form shown in Figs. 4 and 5 an oil pipe L carries a nut M, and the oil casing N is secured to and supported by aid of the nut M. The cylinder A may be attached to the pipe, however, by any other means practical for the purpose.

Below the structure shown in Fig. 1 is the mechanism (not shown) upon which or into which the lubricant is discharged. This mechanism may include the crosshead 95 of a reciprocating engine, for instance, which periodically engages the tripping rod G and raises it in order to momentarily lift the valve B, as above described.

The operation of my device is as follows: The parts being assembled and arranged as shown and described and liquid lubricant being admitted through the tube J or pipe L into the casing A, the liquid lubricant accumulates in the bottom of the casing A or 105 may even fill this casing, or not, depending upon conditions. The crosshead or other moving member above described being now periodically raised into engagement with the tripping member G, the valve B is periodically lifted from its seat, the result being 110 the discharge of a small quantity of the lu-

bricating liquid upon the moving member which conducts it to some part to be lubricated.

I do not limit myself to the precise arrangement shown, as variations may be made therefrom without departing from the spirit of my invention. Neither do I limit myself to the use of a lubricating liquid, as liquids of various other kinds may be collected, 10 charged, and distributed by aid of my device.

Having thus described my invention what I claim as new and desire to secure by Letters Patent is as follows:

- 15 1. A device of the character described comprising a pipe, a casing detachably mounted thereon and provided with an annular seat and with a substantially star-shaped opening exposed below said seat, and
- 20 a valve located within said casing and provided with an annular portion for engaging said seat, said valve being further provided with a tripping rod extending through said opening, said valve being further provided
- 25 with a plurality of passages extending parallel with its axis in order to facilitate the discharge of liquid through said passages and through said opening, said passages being above the seat of said valve.
- 30 2. A device of the character described comprising a depending pipe for supplying oil, a casing detachably mounted upon said depending pipe in order to receive oil therefrom, said casing being provided with 35 a discharge opening and with a valve seat

disposed adjacent said opening, a valve mounted within said casing and provided with a surface for engaging said seat, said valve being further provided with portions extending parallel with the general direction 40 of the casing in order to guide the valve, and a tripping rod carried by said valve and extending through said opening.

3. A device of the character described comprising a casing, means for supplying a lubricant thereto, a spiral spring mounted within said casing, a valve mounted within said casing and engaging said spring, said valve having a generally cylindrical form and being provided with passages extending 50 longitudinally of the valve in the direction of the axis thereof in order to facilitate the travel of the lubricant passing said valve, said passages being above the valve seat, and a tripping rod carried by said valve and extending from said casing.

4. A device of the character described, comprising a casing having a generally cylindrical form, means for supplying a lubricant into said casing, a spring disposed 60 within said casing, a valve mounted within said casing and having a generally cylindrical form, said valve engaging said spring and being provided with passages extending in the general direction of the axis of the 65 casing and parallel thereto said passages being above the valve seat, and a centrally disposed tripping rod carried by said valve and extending axially from said casing.

EINAR AAGE WINHOLT.
